FLUSH VALVE HOUSING

Rodney H. Marchant, Oakland, Calif.

Application March 19, 1956, Serial No. 40,657

Term of patent 14 years

(Cl. D91—3)

Figure 1 is a left hand side elevational view of a flush valve housing, showing my new design;

Figure 2 is a front elevational view thereof;

Figure 3 is a top plan view;

Figure 4 is a right hand side elevational view;

Figure 5 is a rear elevational view; and

Figure 6 is a bottom plan view thereof.

I claim:

The ornamental design for a flush valve housing, substantially as shown.
